UNITED STATES PATENT OFFICE.

JAMES H. DYETT, OF BUFFALO, NEW YORK.

DESIGN FOR A BED-BOTTOM-SUPPORTING FRAME.

SPECIFICATION forming part of Design No. 29,844, dated December 20, 1898.

Application filed November 7, 1898. Serial No. 695,794. Term of patent 3½ years.

► To all whom it may concern:

Be it known that I, JAMES H. DYETT, a citizen of the United States, residing at Buffalo, in the county of Erie and State of New York, have invented and produced a new and original Design for a Bed-Bottom-Supporting Frame, of which the following is a specification, reference being had to the accompanying drawings, forming part thereof.

My invention relates to the shape or configuration of a bed-bottom-supporting frame employed for supporting mattresses of various kinds—such, for instance, as woven-wire mattresses—in beds.

In the accompanying drawings, Figure 1 is a plan view showing my new design, and Fig. 2 is a side elevation of the same.

As shown in the drawings, the leading or material feature of my design consists of a series of four pieces (marked C, D, E, and F, respectively) lying in the same plane with each other and each running from the end piece A to the end piece A' of a rectangular frame, whose side pieces are marked B and B', as shown. The piece C is bent at the 25 points 1 and 2; D is bent at points 3, 4, and 5; E is bent at points 6, 7, and 8, and F is bent at points 9 and 10, all being as shown in Fig. 1. Points 1 and 3 are connected together by the piece G, 2 and 5 by H, 6 and 30 9 by K, and 8 and 10 by L, as shown. The points 4 and 7 are connected by the piece X Z Y.

Having described my invention, what I claim as new, and desire to secure by Letters 35 Patent, is—

The design for a bed-bottom-supporting frame, as herein shown and described.

JAMES H. DYETT.
